W. A. LIGHTHALL.
STEAM ENGINE CONDENSER.

No. 33,951.

Patented Dec. 17, 1861.

UNITED STATES PATENT OFFICE.

WILLIAM A. LIGHTHALL, OF NEW YORK, N. Y.

IMPROVEMENT IN CONDENSERS FOR STEAM-ENGINES.

Specification forming part of Letters Patent No. 33,951, dated December 17, 1861.

To all whom it may concern:

Be it known that I, WILLIAM A. LIGHTHALL, of the city, county, and State of New York, have invented a certain new and useful Improvement in Condensers for Condensing Steam-Engines; and I do hereby declare that the following is a full and exact description of the same, reference being had to the accompanying drawings, and to the letters of reference marked thereon, in which—

Figure 1 is a side view, with the side removed to show its interior. Fig. 2 is a plan or top view taken through the line $x\ x$, Fig. 1; and Fig. 3 is a transverse section taken through the line $x\ x\ x\ x$, Fig. 1.

My improvement is intended, primarily, to be applied to the engines of sea-going steamers to enable them to use fresh water in their boilers; but it is also applicable to the engines of inland steamers when the water is deleterious to the boiler, as is the case on the Mississippi and some others of the western rivers of this country, and it is also applicable to land engines in positions where the water is highly impregnated with lime.

My improvement consists of a combination of a jet and surface-condenser in one instrument, the first entrance of the steam exhausted into it from the engine being met by a jet of cold water (produced by the condensation of the steam exhausted at each revolution of the engine, which water of condensation is cooled down to the temperature of the sea, river, or other cooling-water) and afterward fully condensed by contact with tubes through which passes a current of cooling-water, and by passing through and among a body of cooling-water collected in the lower section of the apparatus.

A is the case or shell of the apparatus, made of cast or plate iron, of sufficient width and height to contain the requisite number of tubes to afford the proper amount of cooling-surface and of such length as to form spaces at each end beyond the tube-sheets B B' for the reception and delivery of the cooling-water.

C is a series of small tubes, of such number and length as to provide collectively a cooling-surface equal to about seventy-five per cent. of the heating-surface of the boilers. They are secured at each end into the tube-

sheets B B' in such manner as to insure their being kept tightly in place. D is a horizontal diaphragm-plate dividing the interior of the apparatus into an upper and lower section for the purpose hereinafter explained.

E E' are two series of division-plates, one placed in the upper and the other in the lower section, as shown, to cause the steam and injection and condensed water to travel an extended distance in contact with the exterior of the tubes C for the purpose of perfectly condensing the steam and cooling the injection-water, so that the latter may be reused.

F is a pipe for the entrance of the cooling-water to pass into and through the tubes C, and F' is a similar pipe, through which that water is carried off after having performed its cooling office. For sea and riversteamers this supply of cooling-water is introduced into and taken from the apparatus by means of the chutes patented to me March 5, 1861; but for land-engines the supply may be obtained by means of a pump worked by the engine.

G is the exhaust-pipe from the cylinder of the engine, through which the steam exhausted from the engine is passed to the condenser to be condensed.

H is the injection-pipe, connected with a hot well or other reservoir, through which the injection-water is passed to meet and operate upon the exhausted steam at its entrance into the apparatus.

I is the delivery-pipe connected with the hot well or reservoir above named, through which the water of condensation and the cooled injection-water is pumped by an "air-pump" back to the hot well or reservoir, the water of condensation being pumped back by a force-pump into the boiler to keep up the head of water in the boiler, and the cooled injection being returned to the apparatus to renew and continue its operation, as above described.

The delivery-pipe I is placed at such height in the lower section of the apparatus as to always retain in that section a body of cooled water, not only to act upon and cool the injection-water passed into it from the upper section, but also to act upon and condense any steam that may pass from the upper section uncondensed.

By the use of the limited jet described the

destructive effect of the first exhaustion of the steam upon and among the tubes of the apparatus is avoided, while it requires but a small air-pump to take off the cooled injection-water and water of condensation, while the continued use of the same injection-water allows the water in the boiler to be preserved at a constant height, as no more water can be returned to the boiler than that made by the condensation of the steam exhausted from the engine.

What I claim as my invention, and desire to secure by Letters Patent, is—

The use of a combined jet and surface condenser, constructed and operated substantially as herein set forth and for the purpose described.

WM. A. LIGHTHALL.
